(57) **CLAIM**

We claim, the ornamental design for an ankle brace, as shown and described.

DESCRIPTION

FIG. 1 is a perspective view of an ankle brace showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the ankle brace in FIGS. 1-7 shown in broken lines are included to show features that form no part of the claimed design.

1 Claim, 5 Drawing Sheets
